US0D1064928S

(12) **United States Design Patent** (10) Patent No.: **US D1,064,928 S**
(45) Date of Patent: ** Mar. 4, 2025

(54) **MOTORCYCLE**

(71) Applicant: **KAWASAKI MOTORS, LTD.**, Hyogo (JP)

(72) Inventors: **Yu Shibuta**, Hyogo (JP); **Uten Kaewsomsri**, Hyogo (JP); **Yumi Murayama**, Hyogo (JP)

(73) Assignee: **KAWASAKI MOTORS, LTD.**, Hyogo (JP)

(**) Term: **15 Years**

(21) Appl. No.: **29/895,776**

(22) Filed: **Jun. 26, 2023**

(30) **Foreign Application Priority Data**

Dec. 27, 2022 (JP) ..... 2022-028028 D
